N.J. Tilghman,

Jaw Trap,

No 9,835,

Patented July 5, 1853.

UNITED STATES PATENT OFFICE.

NOAH J. TILGHMAN, OF SALISBURY, MARYLAND.

IMPROVEMENT IN CROW-KILLERS.

Specification forming part of Letters Patent No. 9,835, dated July 5, 1853.

To all whom it may concern:

Be it known that I, NOAH J. TILGHMAN, of Salisbury, Worcester county, State of Maryland, have invented an Instrument for Killing Crows, which is described as follows, reference being had to the annexed drawings of the same, making part of this specification.

Figure 1 is a perspective view of the instrument set for crows. Fig. 2 is a vertical section of the same when discharged.

Similar letters refer to corresponding parts.

The instrument consists of a sharp-pointed and bearded rod A, resembling a dart or spear let into a sliding block B, inserted into a vertical chamber C, formed in the head of a rough post D, planted where crows are in the habit of frequenting. Between the lower end of the sliding block and the bottom of the chamber in which it slides is placed a helical spring S, said spring being contracted or compressed into a small compass when the dart is drawn down below the head of the post, the dart being held in that position by a dog bearing against an arm or projection E of the sliding block until started by the weight of the crow when he lights upon the top of a section D' of the post, separated from the main body thereof and connected to it by a sliding collar F, fixed to said section or head, sliding over the reduced end of the post, the said collar being attached to a rod G, leading down

to a trigger H, bearing against the dog I. When the crow lights upon the upper end of the sliding section of the post, the trigger is moved and the dog started, thus liberating the dart, which is thrown suddenly upward by the action of the helical spring, piercing the crow on the under part of the body and either killing him instantly or holding him securely to the post until captured. The shank of the dart is provided with an arm E, by which it is drawn down and the spring contracted. The dart is depressed until the point is below the head of the sliding section of the post and is held in that position by the dog, which is brought against the arm and the trigger against the dog.

Having thus described my instrument for killing crows, what I claim as my invention, and desire to secure by Letters Patent, is—

The combination of the dart A, helical spring S, sliding rest or head D', attached to the trigger H, the trigger H, and the dog I, with the hollow post D, in which it is placed.

In testimony whereof I have hereunto signed my name before two subscribing witnesses.

NOAH J. TILGHMAN.

Witnesses.

WM. P. ELLIOT,
ELIJAH J. TILGHMAN.
